UNITED STATES PATENT OFFICE

THOMAS KELLEY MARLOW, OF ANTHAS, TENNESSEE

METALLIC TIE

Application filed March 21, 1930. Serial No. 437,864.

This invention relates to new and useful improvements in metallic ties and more particularly to devices of this character which are especially adapted for use in constructing mine railways, but it is to be understood that a tie in accordance with this invention may be utilized for constructing standard railroads if desired.

The primary object of the invention is to provide, in a manner as hereinafter set forth, a metallic tie of the aforementioned character embodying a construction and rail fastening means whereby the liability of same slipping either longitudinally or laterally will be reduced to a minimum.

Other objects of the invention are to provide a metallic tie of the character set forth which will be simple in construction, strong, durable, efficient in its use and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view in top plan showing a pair of metallic ties constructed in accordance with this invention mounted beneath a pair of rails.

Figure 2 is a cross sectional view taken substantially on the line 2—2 of Figure 1.

Figure 3 is a fragmentary view in longitudinal section taken substantially on the line 3—3 of Figure 1.

Referring to the drawings in detail, it will be seen that the reference numeral 1 designates the body portion of the tie from the opposite ends of which project the integral diverging arms 2 upon which the rails 3 are mounted. As clearly illustrated in Figures 2 and 3 of the drawings, the marginal edges 45 of the body portion 1 and diverging arms 2

as well as the free ends of said arms are provided with integral down turned flanges 4 which are adapted to bite into the road bed and prevent longitudinal or lateral movement of the tie.

Secured to the inner portions of the arms 2 inwardly of the rails 3 are the cleats 5 which constitute braces for said arms 2.

Metallic clamps 6 are detachably secured on opposite sides of the rails 3 on the arms 2 and are provided with longitudinally offset clamping jaws 7 which engage on the base of the adjacent rail. The bolts by means of which the clamps 6 are secured to the arms 2 are designated by the reference numeral 8. 60 If desired, the inner clamp only may be removable and the outer clamp may be permanently secured to the arms through the medium of rivets 9 at the time the ties are manufactured.

It will thus be seen that I have provided a metallic tie which will retain its position on the road bed and also with respect to the rails. The diverging arms 2 provide dual supporting surfaces for the rails on each tie and consequently said ties may be spaced a much greater distance apart than is the practice with ties of a construction in widespread use at present.

It is believed that the many advantages of a metallic tie constructed in accordance with this invention will be readily understood, and although the preferred embodiment of the invention is as illustrated and described, it is to be understood that changes in the details of construction may be had which will fall within the scope of the invention as claimed.

What is claimed is:

A metallic tie of the character described comprising a flat intermediate body portion, integral, flat, diverging arms extending from the opposite ends of the body portion, integral down turned flanges on the longitudinal edges of the body portion and the arms

and on the free ends of the arms, bracing cleats secured transversely to the inner portion of the arms, a clamp permanently mounted on each of said arms adjacent its outer end, a clamp removably mounted on each of said arms inwardly of the stationary clamp and in opposed relation thereto, said stationary and removable clamps constituting means for securing a rail to the arms.

10 In testimony whereof I affix my signature.
THOMAS KELLEY MARLOW.
